(57) CLAIM

The ornamental design for a combination snap hook and compass, substantially as shown and described.

DESCRIPTION

FIG. 1 is a front view of the combination snap hook and compass.

FIG. 2 is a rear view of the combination snap hook and compass, as shown in FIG. 1.

FIG. 3 is a side view of the combination snap hook and compass, showing the compass side as shown in FIG. 1.

FIG. 4 is a side view of the combination snap hook and compass, showing the snap hook side, as shown in FIG. 1. FIG. 5 is an end view of the combination snap hook and compass, as shown in FIG. 1; and,

FIG. 6 is an opposite end view of the combination snap hook and compass, as shown in FIG. 5.

The broken line showing is for illustrative purposes only and forms no part of the claimed design.
